Primary Examiner — Vy N Koenig*Assistant Examiner* — Kimberly Barnes(74) *Attorney, Agent, or Firm* — Temmerman Law Office; Mathew J. Temmerman(57) **CLAIM**

I claim the ornamental design for a flat replacement tile, as shown and described.

DESCRIPTION

FIG. 1 is a top plan view of a flat replacement tile, showing my new design;

FIG. 2 is a front elevation view thereof;

FIG. 3 is a bottom plan view thereof;

FIG. 4 is a rear elevation view thereof;

FIG. 5 is a first isometric view thereof;

FIG. 6 is a second isometric view thereof;

FIG. 7 is a left side elevation view thereof; and,

FIG. 8 is a right side elevation thereof.

1 Claim, 5 Drawing Sheets(56)
